UNITED STATES PATENT OFFICE

EDWARD M. PFAUSER, OF MILWAUKEE, WISCONSIN, ASSIGNOR TO BLACKHAWK MFG. CO., OF MILWAUKEE, WISCONSIN

TOOL HANDLE

Application filed April 16, 1929. Serial No. 355,472.

This invention pertains to improvements in tool handles, and is applicable to such tools as wrenches, bits, and the like, in which the shank of the tool is provided with 5 a rotatable end handle, by means of which the tool is held, and pressure applied thereto.

The invention has primarily for its object the provision of a simple and inexpensive handle of the foregoing character in 10 which novel means are provided for reducing wear at the points of friction, to a minimum.

Incidental to the foregoing, a more specific object is to provide a tool handle with 15 hardened bearings at the points of engagement with the tool shank, so assembled within the handle as to reduce manufacturing costs to a minimum, and provide a snug rigid engagement between the handle and 20 tool.

With the above and other objects in view, which will appear as the description proceeds, the invention resides in the novel construction, combination and arrangement of 25 parts substantially as hereinafter described and more particularly defined by the appended claims, it being understood that such changes in the precise embodiment of the herein disclosed invention may be made as 30 come within the scope of the claims.

In the accompanying drawing, is illustrated one complete example of the physical embodiment of the present invention constructed according to the best mode so far 35 devised for the practical application of the principles thereof.

In the drawing, Figure 1 is a transverse section through a tool handle constructed in accordance with the present invention;

40 Figure 2 is a detail section taken on the line 2—2 of Figure 1.

Referring now more particularly to the accompanying drawing, the numeral 1 designates the shank of a tool, such as a wrench, 45 bit, or the like, and adjacent its upper end, the same is provided with a restricted portion, which results in the annular shoulders 2. Rotatably mounted on the upper end of the shank 1, is a handle 3 comprising a hollow shell formed of upper and lower sections 50

4 and 5, respectively, which sections are preferably formed of sheet metal stampings, of material sufficiently soft to permit proper working.

Secured within the handle between the 55 upper and lower sections, is a hardened bearing plate 6 provided with a recess 7 for the reception of the upper end of the shank 1. To further eliminate friction, and provide an end thrust bearing for the handle, the recess 7 is provided with a rounded projection 8 engaging the end of the shank. The upper and lower sections 4 and 5, as well as the bearing plate 6, are secured together by crimping over the edge of the material of 60 the upper section, as clearly shown in Figure 1.

From the foregoing, it will be readily seen that the hardened plate 6, which receives the upper end of the tool shank 1, 70 serves both as a lateral and end thrust bearing, and inasmuch as the greatest pressure is exerted upon the end of the tool shank, friction is reduced to a minimum through the rounded projection 8, and, the bearing 75 plate, being constructed of hardened material, very little wear occurs.

The lower section 5 is provided with a restricted sleeve extension 9, which snugly receives a hardened split bushing 10 engaged 80 in the restricted portion of the shank and abutting the shoulders 2 to prevent longitudinal movement on the shank.

The handle is secured to the bushing by crimping over the lower edge 11. Thus, in 85 assembled position, the handle has free rotary movement on the shank and is held against longitudinal movement in one direction by engagement of the bearing nib 8 with the end of the shank, and in the opposite direction, by engagement of the split bushing with one of the shoulders 2. Obviously, it is essential that the bushing 2 be split in order to assemble the same upon the restricted portion of the shank prior 90 to assembling the handle on the bushing and crimping over the restricted sleeve extension to provide a permanent assembly.

From the foregoing description, taken in 95 connection with the drawing, it will be obvi- 100

ous that a comparatively simple, durable, and inexpensive structure has been provided, which results in a freely rotatable handle for the shank of a tool and reduces wear to a minimum, in that the parts of the handle for engaging the shank are provided with hardened bearing surfaces, thus permitting the outer shell, forming the handle, to be constructed of relatively soft and inexpensive material, easily formed to the desired shape.

I claim:

1. A tool handle comprising a hollow shell for receiving the shank of a tool, said shell comprising upper and lower sections secured together by crimping the material of one section over the other section, the lower section being provided with a restricted sleeve extension, a hardened plate secured between said sections and provided with a recess for receiving the end of said shank, and a rounded extension in said recess to form an end bearing for said shank, and a split hardened bushing secured in said sleeve extension by crimping over the end of said sleeve, said split bushing engaging an annular restricted portion in said shank to form a bearing for the handle and retain the same against longitudinal movement on the shank.
2. A tool handle including a shank having a restricted portion, shoulders at the ends of said restricted portion, a hardened plate having a central recess for receiving the end of the shank, a rounded extension projecting into the recess to form an end bearing for said shank, a hollow shell enclosing the outer end of the shank comprising upper and lower sections, the lower section having an annular flange to support the edge of the hardened plate, the upper section having its outer edges crimped over the edge of the plate, and the flange on the lower section to connect said section, the lower section being provided with a restricted sleeve extension enclosing the restricted portion in the shank and a split hardened bushing in the restricted portion of the shank and enclosed by the restricted sleeve extension, said bushing being held in place by crimping over the end of the sleeve extension, said split portion engaging one of the shoulders formed by the restricted portion in the shank to form a bearing for the handle and retain the same against longitudinal movement on the shank.

In testimony that I claim the foregoing I have hereunto set my hand at Milwaukee, in the county of Milwaukee and State of Wisconsin.
